UNITED STATES PATENT OFFICE

144,698

DESIGN FOR AN ELECTRIC MEGAPHONE

Henry C. Dalrymple, West Orange, N. J., assignor
to Guided Radio Corporation, New York, N. Y.,
a corporation of New York

Application October 24, 1944, Serial No. 115,943

Term of patent 14 years

(Cl. 26—14)

To all whom it may concern:

Be it known that I, Henry C. Dalrymple, a citizen of the United States, residing at West Orange, in the county of Essex and State of New Jersey, have invented a new, original, and ornamental Design for an Electric Megaphone, of which the following is a specification, reference being had to the accompanying drawings forming a part thereof.

In the accompanying drawings Fig. 1 is a rear perspective view and Fig. 2 is a front perspective view of an electric megaphone showing my new design, the cable having been broken away for convenience of illustration.

I claim:

The ornamental design for an electric megaphone, substantially as shown.

HENRY C. DALRYMPLE.
